United States Patent Office.

CONRAD HERMAN, OF BALTIMORE, MARYLAND.

Letters Patent No. 66,028, dated June 25, 1867.

IMPROVED DEVICE FOR CLOSING BOTTLES.

The Schedule referred to in these Letters Patent and making part of the same.

TO ALL WHOM IT MAY CONCERN:

Be it known that I, CONRAD HERMAN, of Baltimore, in the county of Baltimore, and State of Maryland, have invented certain new and useful improvements in Stoppers for Bottles; and I do hereby declare that the following is a full, clear, and exact description thereof, reference being had to the accompanying drawings, making part of this specification, and to the letters of reference marked thereon, like letters indicating like parts wherever they occur.

To enable others skilled in the art to construct and use my invention, I will proceed to describe it.

My invention consists in making a new and improved bottle-stopper, which may be readily fitted to the necks of different-sized bottles, containing ale, porter, beer, or other similar substances required to be closely bottled up. In the drawings—

Figure 1 represents a side plan view.

Figure 2 represents a horizontal cross-section on the line $z z$ of fig. 1.

Figure 3 represents a longitudinal vertical section on the line $y y$ of fig. 2.

In constructing my bottle-stopper, I make a flat ring, A, with a hinge at e on one side, and provided with lugs, a , on the opposite side, as shown in fig. 2. Through the lugs a I pass a screw, b , to draw and hold them together, as shown in figs. 1 and 2. To the ring A I attach two flat upright arms, d d' , and to the arm d' I pivot a cap, B, at i , and provide the other arm d with a lug, o , and the cap B with a corresponding lug, n , as shown in figs. 1 and 3. Through the lugs n and o I pass the screw t , which draws them tightly together and holds them. The cap B I make hollow, and provide it on the inside with a rubber cushion, C, as shown in fig. 3.

In using my bottle-stopper, I release the screw t , so that the cap B may be raised. I then release the screw b , so that the ring A may be adjusted to the neck of the bottle to which the stopper is to be applied. This done, I draw the lugs a together and fasten them by means of the screw b , which at the same time causes the ring A to clasp the neck of the bottle as closely as may be desired. The cap B is then brought down over the top of the bottle and fastened down by means of the screw t . As the screw t is turned the rubber cushion C is pressed on the top of the bottle, which is thus tightly closed.

My bottle-stopper can be made of various sizes, and the same size may be used for different bottles, as it is obvious it can be readily taken from one and placed upon another.

Having thus described my invention, what I claim, is—

The hinged clasp A, fastened by means of the lugs a and screw b , and having upright arms, d d' , with the cover B pivoted to d' and fastened to d by means of the lugs o n and screw t , when arranged to operate substantially as described and set forth.

CONRAD HERMAN.
